Primary Examiner — Kelley A Donnelly(74) *Attorney, Agent, or Firm* — Andrew F. Young, Esq.;
Lackenbach Siegel, LLP(57) **CLAIM**

The ornamental design for a display stand, as shown and described.

DESCRIPTION

This application relates to, but does not claim priority from, U.S. patent application Ser. No. 62/500,125 filed May 2, 2017, the entire contents of which are incorporated herein by reference.

FIG. 1 is a front top perspective view of a display stand of my invention.

FIG. 2 is a bottom rear perspective view thereof.

FIG. 3 is a top plan view thereof.

FIG. 4 is a bottom plan view thereof.

FIG. 5 is a front elevation view thereof.

FIG. 6 is a rear elevation view thereof.

FIG. 7 is a left side elevation view thereof; and,

FIG. 8 is a right side elevation view thereof.

The surfaces are lightly lined for contour. No claim is made to portions of the design which are not shown. The dash-dot lines indicate disclaimed subject matter.
